New York, N. Y., a corporation of New York

Application July 7, 1936, Serial No. 89,283

2 Claims. (Cl. 101—93)

This invention relates to printing machines and more particularly to machines of the record card controlled type.

The principal object of the invention is to provide an attachment for printing tabulators for controlling the operation of the printing hammers. In printing tabulators the differentially positioned type bars are arranged to connect individual type hammers for tripping when the type bars are positioned to present certain characters to the printing line and to prevent the selection of the hammers when other characters are at the printing line. According to the present invention mechanism is provided under control of a special perforation in the record card for causing the tripping of all the hammers regardless of the positioning of the various type bars.

Various other objects and advantages of the invention will be obvious from the following particular description of one form of mechanism embodying the invention or from an inspection of the accompanying drawings; and the invention also constitutes certain new and useful features of construction and combination of parts herein-after set forth and claimed.

In the drawings:

Fig. 1 is a sectional view taken through the type bar and hammer operating unit of a tabulator.

Fig. 2 is a position view of parts shown in Fig. 1, showing the improvements of the invention in another position.

Fig. 3 is an outside view of the printing section of the tabulator showing certain control and drive connections.

Fig. 4 is a detail view looking in the direction of lines 4—4 of Fig. 1 and showing the column splitting mechanism.

Fig. 5 is an end elevation looking from the left in Fig. 1.

Fig. 6 is a detail view showing the manner in which the type bar controls the coupling of the hammer latch.

Fig. 7 is a fragment of a record card.

Fig. 8 is a circuit diagram.

Fig. 9 is a timing diagram of the essential circuit controlling devices.

Fig. 10 is a specimen of a record.

The printing mechanism may be of any suitable form but for convenience may be assumed to be substantially identical with that described in the patent to A. W. Mills, No. 2,016,682, granted October 8, 1935. This mechanism includes the usual platen 10 (Fig. 1) and a number of vertically movable type bar assemblies in-

cluding carriers 12 slidably mounted on each of which is a type head 13. Each type head has type elements 14 slidably horizontally therein, which are adapted to print the numerals 1 to 9 and the letters A to Z. The type elements are arranged as indicated in Fig. 1 with the digits interspersed among the alphabetic characters. The carrier 12 is positioned by a stopping pawl 15 which is designed to engage the teeth 16 in the carrier. This engagement will select the digit 10 type for printing. To select the alphabetic type the type head 13 is displaced with respect to the carrier 12, one, two, or three steps to select the various alphabetic type. The manner in which this selection is effected is fully explained in the 15 patent referred to and since a detailed explanation of the manner in which the type bar is positioned forms no part of the present invention, such explanation need not be given here.

Explanation will first be made of the manner 20 in which the tripping of the hammers to take an impression from a selected type bar is normally effected after which the invention will be more particularly described.

Associated with each type head 13 is a printing hammer 17 which is normally held in the position shown in Fig. 1 by a latch 18 and is urged by a spring 19 into printing action. The latch 18 has pivoted thereto, at 20, a hook 21 having a tail 22 in engagement with a lever 23 which is pivoted at 24 to the frame of the machine. The rightwardly extending arm of lever 23 lies in the path of a block 25 (see Fig. 6) which is secured to the carrier 12. When the type bar is elevated to present any but the three lower- 35 most type elements 14 to the printing line, the hook 21 remains in the position shown as block 25 does not rise sufficiently to engage lever 23.

After all the type bars have been positioned, the bail 26 which is secured to shaft 27 is rocked 40 clockwise after the bail 28 which is secured to shaft 29 has been rocked in the same direction and those hooks 21 which lie in the path of bail 26 will be drawn toward the left to draw their respective latches 18 away from the latching 45 arms of hammers 17 and the latter will consequently be urged against the type elements by springs 19. The mechanism for rocking the bails is shown in Fig. 3 wherein shaft 27 has secured thereto an arm 30 which has slotted link connection 31 to a bell crank 32 secured on shaft 29. Through a link 33 the bell crank 32 is connected to an arm 34 secured upon the shaft 35. The shaft 35 also carries a double-armed cam follower 36 whose rollers engage a pair of comple- 55

mentary cams 37 carried by the drive shaft 38 of the machine. This mechanism is the usual construction for operating the hammer restoring and latch tripping bails of the machine.

If the type bar rises to present any of the three lowermost type or the blank position to the printing line, the upper end of the block 25 will engage and rock the arm 23 to shift hook 21 to the position shown in Fig. 6. It will be apparent that tripping of the hammers of type bars so positioned cannot take place through the related hooks 21. These lowermost type positions generally represent zeros or special characters. In the present case, the lowermost type element is termed the alphabetic zero and the uppermost is termed the numerical zero and the other when the machine prints alphabetic characters and the other when the machine is set for printing numerical data only. When it is desired to effect printing from these lowermost type elements, the so-called and well known column splitting devices are employed. The column splitting mechanism is substantially identical with that described in the Peirce Patent No. 1,867,026, granted July 12, 1932. A coupling member 40 (Figs. 1, 2, and 4) is pivoted to the upper end of each latch 18. The members 40 have narrow tongues 41 which underlie bent-over lugs 42 formed in the adjacent latch 18 which lugs act as stops to limit counterclockwise movement of members 40. A lug 43 formed in each member 40 permits only limited clockwise movement of each member by contact with the edge of the latch 18 to which said member is pivoted. A short arm 44 formed in each member 40 has a rivet or boss adapted to engage holes 45 in latch 18 to retain members 40 in the operative position of Fig. 1 or the alternative inoperative position in which lug 43 engages latch 18. Each member 40 has also an abutment 46 adapted to engage the lug 42 of the next adjacent latch 18 to the one on which said member is pivoted.

Referring to Fig. 4, it will be assumed that the three coupling members 40 shown correspond to the units, tens and hundreds denominational orders ranging from bottom to top respectively of a bank assigned to print data and all are in the position of Fig. 1. If the hundreds type bar now moves to print a "4", for example, its latch 18 will be rocked clockwise (Fig. 1) as described above, to release the hammer for the hundreds type bar. The abutment 46 of the hundreds hammer coupling will, by engagement with the lug 42 of the tens latch 18, rock the latter clockwise also. The latch 18 of the units type bar will also be operated by the tens latch 18 due to the abutment 46 of the coupling member 40 of the tens latch engaging the lug 42 of the units latch and rocking the units latch 18 clockwise with reference to Fig. 1. Thus, if neither of the units or tens type bars are arrested in one of the numerical positions 1 to 9 or alphabetic positions A to Z, inclusive, the three type bars corresponding to the three coupling members 40 shown in Fig. 4 will print "400." Now, if the upper member 40 (Fig. 4) associated with the hundreds type bar is moved clockwise (Fig. 1) until its lug 43 stops further movement of the said member, the abutment 46 of this member will move to a position below the lug 42 of the tens latch 18. As a result, the moving of the hundreds type bar to the "4" position as before will cause an ineffectual movement of the coupling member of the hundreds latch 18 and 75 neither the tens nor units latches will be oper-

ated so that only the numeral "4" will be printed.

It will be seen that the coupling members 40 may be selectively set to inactive position to split the solid bank of type bars into arbitrary groups and under these conditions any type bar assuming the position to present either of the zero type elements or the special character type element will, through members 40, cause zeros to be automatically printed to the right of the operated type bar up to the point where a coupling member 40 is set to inactive position. It follows, therefore, that in accordance with the operation just described, printing from the three lowermost type elements 14 cannot take place unless a higher order type hammer has been tripped and the column splitting latches are properly positioned to transmit the tripping action to the bars whose hooks 21 are disabled. The foregoing is the normal manner of operation of the so-called splitting mechanism.

For certain types of work it may become desirable to effect printing from these lowermost type without requiring the tripping of a higher order position. Such problems arise where alphabetic information, such as names and addresses, is to be printed on a record sheet above columns of amounts which require the use of the column splitting devices to prevent printing of undesirable zeros. An example of such application is shown in Fig. 10. Each printed line represents data perforated on a separate record card. With the type bars positioned in order to correctly control the printing of zeros in the column of figures beneath the address, the members 40 are set to inactive position at the points indicated by the arrows. Thus, the "6" in the first line will not cause the zero to print to its right and in the second line, the "1" in the second column will cause the printing of the zero to its right. With the column splitting devices so positioned, printing would be controlled invariably for each card in accordance with such setup so that if an address card bearing the street number, as indicated in the second line of Fig. 10, controls the setting of the type bars, the zero in the street number would not be printed because of the split at such position. Also with a code number, such as appearing in the third line, the zero to the left of the numeral "6" would not be printed because of the split at this point.

Another case wherein it is desirable to cause printing from the lowermost zero type without regard to the printing of a character in a higher order is where the zero type are used to represent the letter "O". Such condition arises in connection with the printing of the Swedish alphabet in which the letter "O" position is utilized for one of the special characters in the Swedish alphabet and the zero type position is used to represent the letter "O".

Referring now to Fig. 1, the mechanism which comprises the improvements of the present invention will be described. Secured to the shaft 21 (see also Fig. 5) is an arm 50 which at its free end supports a rod 51. To this rod is secured a pawl 52 and a cam member 53. The pawl 52 lies in the plane of a member 54 which is loosely mounted on shaft 21 and which has a notch 55 therein. The cam member 53 rides on a pin 56 in one end of a link 57 which is pivoted at 58. The link 57 normally occupies the position shown in Fig. 1 and as the shaft 21 rocks, carrying with it the arm 50 and rod 51, the camming element 53 slides along the pin 56. If the link 57 is rocked from the position 75

of Fig. 1 to that of Fig. 2, it will cause rocking of cam member 53 and rod 51 to lower the pawl 52 into the notch 55 of member 54 so that upon the next clockwise rocking of shaft 21, the pawl 52 will engage the edge of notch 55 and cause clockwise rotation of the member 54. The member 54 is provided with an extending arm 59 at whose extremity is pivoted a bail 60 which extends across along the left edges of the latches 18. The arm 59 and the bail 60 form a toggle which, as arm 59 moves clockwise, tends to straighten as the bail is guided along the fixed plate 61 and, due to such movement, the bail will engage and rock all of the hammer latches 18 to release all of the type hammers 17.

In this manner, whenever link 57 is rocked counterclockwise, all of the hammers 17 will be tripped and printing will take place from whatever type elements may be presented to the printing line regardless of the prior setting of the column splitting members 40.

The rocking of link 57 is controlled from a special perforation which is made in each record card for which such universal tripping of the latches is desired. More specifically, with reference to Fig. 10, the record cards containing data relating to the address may be punched with a special so-called "X" hole in a selected column of the card. The manner in which this special perforation controls the operation of the attachment will now be explained.

In Fig. 8 are shown the analyzing brushes UB and LB which are successively traversed by each record card and the perforated data thereon sensed to control the operation of the zoning magnets 62 and the type selecting magnets 63, whose conjoint action controls the position of the type elements in the manner fully set forth in the patent referred to. A magnet 64 is provided, which, as will be explained, controls the rocking of the link 57 to cause tripping of all the hammers. This magnet is designated as the hammer trip magnet and its energization will take place under control of a special perforation in the "11" index point position of a record card, such as indicated at "X" in Figs. 7 and 8. Upon sensing of this perforation by one of the upper brushes UB, a circuit is completed from line 65, upper contact roller UCR, "X" perforation, brush UB, wire 66, plug connection 67, pickup winding of a relay R8, cam contacts CF6, timed to close when the "X" hole is at the brush UB, upper card lever contacts UCL, to line 68. Energization of relay R8 will close its contacts R8a to provide a holding circuit traceable from line 65, wire 69, contacts R8a, upper holding winding of relay R8, cam contacts CF22, to line 68. As indicated in Fig. 8, this holding circuit will be maintained throughout the remainder of the cycle and during the first half of the next following cycle, during which the record card having the "X" perforation will traverse the lower brushes LB, during which time the data perforations will be sensed by these brushes to position the type carriers. Energization of relay R8 will also cause closure of its contacts R8c, and if switch 70 is in its full line position, a circuit will be completed during the next cycle through cam contacts CF14 which extends from line 65 through cam contacts CF14, relay contacts R8c, switch 70, hammer trip magnet 64, to line 68. In this manner, record cards containing the special "X" perforation will cause tripping of all the hammers to print from all

the type bars which may have been positioned. If switch 70 is in its dotted line position, the operation would be reversed; that is, the hammer trip magnets 64 will be energized each cycle when cam contacts CF14 close, the circuit being traceable from line 65, contacts CF14, normally closed relay contacts R8b, switch 70, hammer trip magnet 64, to line 68. In this case, the energization of relay R8 in response to the sensing of an "X" hole will cause opening of contacts R8b and the operation of the hammer trip magnet will be suppressed for cards having this perforation.

The right hand end of link 57 (Figs. 1 and 3) has pin and slot connection with a link 71 which is pivoted at 72 and whose opposite end has connection with a vertical link 73 whose lower end is connected to an arm 74 normally held in the position shown in Fig. 3 by the armature 75 of the magnet 64. Arm 74 is pivoted on a stud 76 on which is also pivoted a bell crank 77 having a pin 78 underlying the arm 74. The lower arm of the bell crank lies in the path of the roller 79 on arm 80. Arm 80 is part of the linkage controlled by the complementary cams 81 which serve to reciprocate the type bars once each cycle of the machine and during the operation, roller 79 causes counterclockwise rocking of bell crank 77 to raise arm 74 slightly away from armature 75. It is at this time that magnet 64 may be energized and if energization takes place, arm 74 will be permitted to move in a clockwise direction and rocking of link 57 will consequently take place.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In a printing machine having a plurality of positionable type carriers, printing hammers, one for each carrier, an actuator, means controlled by each carrier for causing said actuator to trip the related hammer when the carrier is in certain positions and for preventing tripping by said actuator when the carrier is in other positions, in combination with record controlled means and a second actuator controlled thereby for causing tripping of said hammers when the carriers are in any printing position.

2. In a record controlled printing machine, a plurality of type carriers positionable to present significant digits and zeros to the printing line, printing hammers and latches therefor, an actuator means controlled by said carriers for connecting said latches to said actuator to trip their related hammer latches only when significant digits are presented to the printing line, settable connections between said hammer latches for causing a tripped latch to trip a selected number of adjacent latches whose related carriers are positioned to present zeros to the printing line, a second actuator and auxiliary means controlled by a special perforation in a record card for causing said second actuator to effect direct tripping of all the hammer latches irrespective of the positioning of their related carriers and independently of said first named actuator.

ALVIN E. GRAY.
